UNITED STATES PATENT OFFICE.

WILLIAM W. WINGO, OF WILBURTON, OKLAHOMA, ASSIGNOR OF FIFTY-ONE PER CENT
TO E. L. TERRY, OF BRINKLEY, ARKANSAS.

SIGNAL DEVICE.

Application filed March 29, 1926. Serial No. 98,353.

This invention relates to signal devices adapted particularly for use upon motor vehicles.

The primary object of this invention is the provision, in a manner as hereinafter to be set forth, of a motor operated motor vehicle signal designed to give warning by reproducing the human voice, or by mimicking the call of an animal or the note of a fowl, to indicate to a pedestrian or to another vehicle the presence of the vehicle upon which the signal is mounted.

Another object of the invention is the provision, in a manner as hereinafter set forth, of a signal device designed for use in connection with land vehicles, which makes use of a disc record, upon which an impression has been made, and from which impression a needle or stylus transmits to a diaphragm movements which cause the diaphragm to project from a horn notes indicating the position or the contemplated movement of the vehicle.

A still further object of the invention is the provision, in a manner as hereinafter set forth, of a vehicle signal of the type above set forth and having means operable by the operator of the vehicle whereby the stylus may be lifted from the record or replaced thereon as desired without stopping the operation of the mechanism of the signal.

A further and final object of this invention is the provision, in a manner as herein-after set forth, of a motor operated vehicle signal of the character set forth, of simple, light and durable construction, easily manipulated, efficient, dependable, and inexpensive to manufacture and install.

The invention will be best understood from a consideration of the following detailed description taken in connection with the accompanying drawings forming a part of this specification, with the understanding that the invention is not confined to any strict conformity with the showing of the drawings, but may be changed and modified so long as such changes and modifications mark no material departure from the salient features of the invention as expressed in the appended claim.

In the drawings:

Figure 1 is a vertical section taken through the housing encasing the mechanism of this device, showing the mechanism therein in side elevation.

Figure 2 is a horizontal section taken upon the line 2—2 of Figure 1.

Referring now to the drawings in detail wherein like numerals of reference indicate corresponding parts throughout, there is indicated by the numeral 1, the mechanism housing or casing having a removable side 2 for access to the mechanism contained therein, and having the bottom open as shown. Secured to the underside of the casing is a motor housing 3 having a flange 4 formed about the top thereof, which flange is secured to the underside of the casing 1.

Within the housing there is placed a gear supporting frame constituting top and bottom plates 5 and 6, respectively, these plates being spaced apart by means of the tubular posts 7, through which posts and plates there extends a bolt 8, the lower end of which bolt projects through the flanged portion 9 of the bottom of the casing and through the flange 4 of the motor housing to receive the retaining nuts 10, which nuts act, besides holding the plates 5 and 6 in position, to secure the motor housing to the underside of the casing 1 and also to securely position the gear frame in the casing 1.

Supported in any suitable manner within the housing 3 is an electric motor 11 fed by electric wires 12, which extend to a switch mechanism of any desirable form (not shown), located at a convenient point for the driver of the vehicle. The shaft 13 of the motor is positioned vertically and extends upwardly through the bottom plate 6 of the gear frame and carries upon its upper end a pinion 14. This pinion meshes with a gear 15 carried upon a vertical shaft 16 secured between the plates 5 and 6, as shown, and this shaft also carries thereon a pinion 17, which in turn, meshes with a large gear 18, carried upon the vertical shaft 19, also secured between the plates 5 and 6 as shown, and this shaft extends through the upper plate 5 and carries upon its upper end above the plate 5 a revoluble platform or turntable 20.

Positioned upon the platform 20 is a disc record 21, having a single groove 22 therein, this groove being formed by the vibration of the impression needle actuated by the voice or sound which is to be reproduced by this mechanism, as the desired warning signal. This plate 21 has a central aperture therethrough through which the upper end of the

vertical shaft 19 extends, and upon the upper end of this shaft there is threaded a nut 23 which bears against the disc 21 and acts to retain the same firmly in position upon the platform 20.

Extending through one side wall of the housing 1 is the contracted rear portion 24 of a horn 25. The contracted portion 24 upon the inside of the housing carries a collar 26 which bears against the inner face of the wall and is secured thereto to retain the horn in the proper position. Over the inner end of the reduced portion 24 there is slipped one end of the rubber tube or nipple 27, the other end of which engages over the tubular portion 28 of a diaphragm casing 29. This casing is similar to the usual phonograph diaphragm reproducing mechanism and carries a diaphragm 30 at one side to which is connected a vibrating arm 31 and which in turn is adapted to receive and hold a stylus 32 adapted to travel in the groove 22 of the disc record 21.

Secured to the top plate 5 by means of a right angled foot 33 is a vertical standard 34 which extends upwardly in the casing and at one side of the platform 20, and this standard has pivotally secured at 35 a bell crank member having a vertical short arm 36 and a horizontal long arm 37. Depending from the free end of the long arm 37 is a link 38 having its lower end formed to provide a saddle member 40 which is secured over the tube 28 of the reproducer member.

Connected to the free end of the vertical arm 36 is a cord or wire 39 which extends to a position accessible to the operator of the vehicle, and when the operator desires to remove the stylus 32 from the record 21 without switching off the motor 11, the same can be accomplished by pulling the wire 39 which will lift the reproducer member from the record. The flexible tubing 27 is provided to allow for this movement.

From the foregoing description it will be readily seen that a simple, efficient and dependable motor vehicle signal has been produced by means of which a voice can be made to call out to pedestrians or to other vehicles to warn the same or to indicate a contemplated change in direction of movement.

Having thus described my invention what I claim is:

In a signal device of the character described, a turntable, means for rotating the table, a reproducer adapted for engagement with a sound producing disc when upon the table, a stationary horn at one side of the table, a tubular flexible union between the reproducer and horn, a lifting device above the reproducer and connected with the latter to elevate it from the disc, and means shiftable from a point remote from the lifter to actuate the same.

In testimony whereof, I affix my signature hereto.

WILLIAM W. WINGO.
